PUMP OR MOTOR

Walter Ernst, Mount Gilead, Ohio, assignor, by
mesne assignments, to The Hydraulic Press
Corporation, Inc., Wilmington, Del., a corpora-
tion of Delaware

Application May 23, 1934, Serial No. 727,081

3 Claims. (Cl. 103—161)

This invention relates to fluid pressure pumps or motors, and especially to such pumps or motors as have primary and secondary rotors with radially disposed pistons and cylinders interconnecting them.

One object of my invention is to provide a fluid pressure pump or motor having primary and secondary rotors interconnected by pistons which reciprocate radially in the cylinder bores and tangentially in secondary rotor guide blocks, the piston crossheads having surface grooves and conduits leading to these grooves for the purpose of supplying lubricant to the thrust surfaces.

Another object is to provide such a pump or motor wherein the piston is provided with a portion arranged to be guided on opposite sides during its reciprocation by correspondingly formed portions on the primary rotor.

Another object is to provide such a pump or motor wherein the thrust surface of the crosshead is grooved to receive an extended portion of the piston, this extended portion being adapted to engage guide portions on the primary rotor arranged on opposite sides thereof, the crosshead proper being likewise adapted to engage the secondary rotor.

Another object is to provide such a pump or motor wherein the rotating parts are supported on preloaded ball bearings which serve to place a preliminary load thereon in order to take out most of the elastic deformation thereof.

Another object is to provide means whereby the outer end of the pintle and primary rotor will be supported by means associated with the drive shaft, the latter being rotatably supported in the casing so that a compact and yet efficient construction results.

In the drawings:

Figure 1 is a central vertical section through the pump or motor of my invention, taken in a transverse plane, passing through the axes of the cylinder bores;

Figure 2 is a central longitudinal vertical section therethrough;

Figure 3 is a front elevation of the primary rotor used in the pump or motor of my invention;

Figure 4 is a side elevation, partly in section, of the primary rotor shown in Figure 3;

Figure 5 is a side elevation, partly in section, of the piston and crosshead of this invention;

Figure 6 is an end elevation of the piston and crosshead shown in Figure 5;

Figure 7 is a top plan view of the piston and crosshead shown in Figure 5;

Figure 8 is a side elevation of the crosshead guide block used in this pump or motor;

Figure 9 is a central longitudinal horizontal section through a modified form of pump or motor employing pre-loaded ball bearings.

Referring to the drawings in detail, Figure 2 shows a hydraulic pump or motor having a casing composed of end plates 1 and 2 interconnected by an annular casing ring 3, as by the bolts 4. The end plate 1 is provided with a boss or projecting portion 5, having a bore 6 in which is mounted a pintle 7. The outer end of the pintle 7 is threaded as at 8, these threads being engaged by the nut 9. The tightening of the nut 9 causes the pintle 7 to be firmly held against the projecting boss 5 by the pintle shoulders 10 at one end and the nut 9 at the other end. The pintle 7 is provided with the usual internal bores 22, 23, 24, and 25 for the passage of fluid, these communicating with the external piping by means of transverse passageways, such as 11, in the projecting boss 5.

The inner end of the pintle 7 is provided with a reduced diameter portion 12 which passes through a bore 13 in the primary rotor 14 of the machine. This primary rotor 14 is rotatably supported by means of tapered roller bearings 15 having their inner races 16 mounted upon the pintle portion 12, and their outer races 17 set into countersunk portions 18 and 19 respectively in the ends of the primary rotor or cylinder barrel 14. The pintle portion 12 is provided with valve openings 20 and 21 communicating with the pintle conduits 22, 23, 24, and 25.

The end of the pintle portion 12 is provided with an end plate 26 secured thereto by the cap screws 27. This end plate 26 serves to retain the inner races 16 of the roller bearings 15 in place on the pintle portion 12. The cylinder barrel 14 is likewise provided with the annular grooves 28 and 29, encircling the pintle portion 12 on each side of the valve openings 20 and 21. The primary rotor or cylinder barrel 14 is also provided with radially disposed cylinder bores 29a, five being shown, although a greater or lesser number can be used, these communicating through their entrance ports 30 with the valve openings 20 and 21.

Power is communicated to or from the primary rotor or cylinder barrel 14 by means of the drive shaft 31 having the spider portion 32 attached thereto. The spider portion 32 is secured to the primary rotor 14 by means of countersunk screws 33. The drive shaft 31 is rotatably mounted in the tapered roller bearings 34 and 35, whose inner races 36 and 37 are mounted upon the en-

larged portion 38 of the drive shaft 31, and whose common outer race 39 is mounted in a bore 40 in the projecting boss 41 of the end plate 2. Leakage around the drive shaft 31 is prevented by means of the sealing ring or packing 42, which is held in place against the drive shaft 31 by means of the gland 43. The latter is held against the projecting boss 41 by means of the countersunk screws 44.

10 The outer races 17 of the roller bearings 15 are held in position within the countersunk portions 19 and 18 respectively by the projecting portion 51 of the spider 32 on the one end, and by the retaining ring 52 bolted to the primary rotor 14 by means of countersunk screws 53 on the other end.

15 The annular casing portion 3 is provided with diametrically opposite bores 54 and 55, through which pass shifting rods 56 and 57. These rods are threadedly secured within the bores 58 and 59 of the secondary rotor shift ring 60 in such a manner that the axis of the latter may be shifted relative to the axis of the pintle 7. In this manner the shift ring 60 may be placed in an eccentric position relative to the pintle 7. Within the secondary rotor shift ring 60 are mounted the outer races 61 of the tapered roller bearings 62, these being held in place by the retaining rings 63 and 64 on opposite sides thereof, through the agency of the countersunk screws 65. The inner races 66 thereof have tapered internal bores 67, which are adapted to be held on the tapered surfaces 68 of the secondary rotor halves 69 and 70 by the retaining rings 71 and 72 through the agency of countersunk set screws 73. In this manner the secondary rotor halves 69 and 70 are free to rotate within the secondary rotor shift ring 60.

20 The secondary rotor halves 69 and 70 may be collectively and generally designated as the secondary rotor 74, being interconnected by the crosshead guide blocks 75. The latter are clamped between the annular grooves 76 and 77 by means of the bolts 78. The assembly of the guide blocks 75 and the secondary rotor halves 69 and 70 is encircled by the annular lubricant retainer 79.

25 The guide blocks 75 are provided with tangentially grooved portions 80, which are adapted to reciprocably receive the crossheads 81. The latter are attached to extended portions on the outer ends of the pistons 82 which in turn reciprocate radially within the cylinder bores 29a of the cylinder barrel or primary rotor 14. The crossheads 81 are preferably integral with the pistons 82, thus providing the desirable rigidity inherent in a solid piece of metal.

30 The crosshead 81 of the piston 82 (Figures 5 to 7 inclusive) has a thrust surface 83 which transmits the load to the thrust surface 84 of the guide block 75, or receives the thrust therefrom. The thrust surface 83 of the crosshead 81 is provided with transverse grooves 84a for the purpose of distributing lubricant conducted thereto through the conduits 85 passing through the crosshead 81. The surface of the crosshead opposite to the thrust surface 83 is provided with channeled portions 86 having side ridges 87 which also slide within the tangential grooved portions 80 of the crosshead blocks 75, whereas the channeled portions 86 are slightly larger than the arcuately formed projections 88 extending outward from the primary rotor 14 (Figures 2, 3, and 6), the projection 88 being thereby freely received within the channeled portions 86 by rea-

son of this clearance. The arcuate projecting portions 88 terminate in the guide walls 89 at the outer ends of the cylinder bores 29a, the guide walls 89 serving to engage the outer extended portions of the pistons 82 immediately beneath their crossheads 81.

35 In operation, the secondary rotor shift ring 60 is moved by means of shift rods 56 and 57 until the secondary rotor 74 has its axis located eccentrically with respect to the axis of the primary rotor 14 and the pintle portion 12. When power is applied to the drive shaft 31, assuming that the machine is being used as a pump, the pistons 82 are caused to reciprocate radially in their bores 29a by reason of this eccentric arrangement of the axis of the two rotors; and at the same time the piston crossheads 81 reciprocate tangentially in the grooved portions 80 of the crosshead guide blocks 75. Due to the centrifugal force set up in the operation of the machine, oil is thrown outward in a radial direction and passes through the conduits 85 of the crosshead 81 into the grooves 84a on the thrust surface 83 thereof, lubricating the latter. This provides a film of lubricant between the thrust surface 83 of the cross head 81 and the opposite thrust surface 84 of the guide block 75. At the same time, the outer extended portions of the pistons 82 immediately beneath their crossheads 81 slidingly engage the guide walls 89 of the projecting portions 88 on the primary rotor 14, thus providing an additional guiding influence upon the pistons 82, which supplements the guiding action of the cylinder bores 29.

40 In practice it has been found that very slight tolerances must be maintained between the rotating parts in order that the machine shall function efficiently without excessive leakage. Accordingly, it is necessary to insure a close fit of all bearings, yet prevent metal-to-metal contact between them. To this end, the tapered roller bearings 15 and 62 have been used in preference to other forms of bearings since they provide a greater measure of adjustability. The inner races 66 of the outer roller bearings 62 are internally tapered, as at 67, and mounted upon the externally tapered portion 68 of the secondary rotor halves 69 and 70 in order to facilitate quick and easy assembling of the pump as well as the disassembling thereof.

45 In previous forms of pumps or motors employing pintles of this nature, it has been frequently found that the pintle will deflect slightly under a heavy load and cause metal-to-metal contact to take place. In the present invention, however, this deflection is effectively reduced by means of the tapered roller bearing construction. The deformation of the bearing elements themselves is practically eliminated when the bearings are given a slight amount of pre-loading. 50 The reason for this is that a study of the behavior of antifriction bearings having multiple rotating elements shows that the largest amount of elastic deformation occurs at a light loading, and that as the load increases the deformation increases at a 55 much slower rate. Thus by slightly pre-loading the bearing, it is possible to take out most of the elastic deformation thereof.

55 In Figure 9 is shown a modified form of pump or motor employing ball bearings instead of roller 60 bearings. These ball bearings 90 and 91 may be arranged singly or in pairs, the latter construction being shown. In use these ball bearings 90 are given a slight amount of preloading in order to remove the elastic deformation thereof, as ex- 65

plained above. This substantially prevents a further deformation of the ball bearings 90 and 91 between the outer races 92 and 93 and the inner races 94 and 95.

- 5 The support of the entire outer end of the cylinder rotor 14 and the pintle portion 12 by the drive shaft portion 38 in the roller bearing 34 and 35 gives a construction which contributes to extremely close fits of the rotating parts, yet prevents excessive deformation thereof. In this manner a very solid construction is obtained and metal-to-metal contact substantially done away with.
- 10

It will be understood that the machine of this invention can be employed either as a pump or as a motor. In using it as a pump, power is applied to the drive shaft 31 and oil supplied through the valve openings 20 and 24 in the pintle 7. In using the machine as a motor, however, fluid under pressure is supplied through one of the valve openings 20 or 21, whereupon the eccentric arrangement of the primary and secondary rotors causes the pistons 82 to reciprocate, thus applying power to the secondary rotor or cylinder barrel 14; this power is then communicated to the drive shaft 31 through the spider 32 forming a connection therebetween.

It will be understood that in the present invention I have provided preloaded ball bearings which are slightly larger in diameter than the space between their races, the balls being forced into this space in such a manner that the clearance between the races and the balls is substantially zero. In this manner I maintain a fluid-tight connection between the fluid-distributing valve or pintle and the cylinder barrel at high pressures, and yet prevent metal-to-metal contact therebetween.

It will be understood that I desire to comprehend within my invention such modifications as may be necessary to adapt it to varying conditions and uses.

Having thus fully described my invention what I claim as new and desire to secure by Letters Patent is:

1. A fluid pressure pump or motor including a cylinder body, a fluid distributing valve, said cylinder body and said fluid distributing valve being mounted for rotation relatively to one another, 45 cylinders in said cylinder body arranged to com-

municate with said fluid distributing valve, pistons arranged to reciprocate in said cylinders, means for reciprocating said pistons, and preloaded ball bearings mounted between said cylinder body and said distributing valve, the diametral clearances of said preloaded ball bearings being reduced to substantially zero, the clearance between said cylinder body and said fluid distributing valve being greater than the total diametral clearance of said preloaded ball bear- 10 15 ings.

2. A fluid pressure pump or motor including a cylinder body, a fluid distributing valve, said cylinder body and said fluid distributing valve being mounted for rotation relatively to one another, cylinders in said cylinder body arranged to communicate with said fluid distributing valve, pistons arranged to reciprocate in said cylinders, means for reciprocating said pistons, and preloaded ball bearings mounted between said cylinder body and said distributing valve, the diametral clearances of said preloaded ball bearings being reduced to substantially zero, the clearance between said cylinder body and said fluid distributing valve being greater than the total 20 25 diametral clearance of said preloaded ball bearings, said preloaded ball bearings being arranged in paired assemblies at opposite ends of said cylinder body.

3. A fluid pressure pump or motor including a cylinder body, a fluid distributing valve, said cylinder body and said fluid distributing valve being mounted for rotation relatively to one another, cylinders in said cylinder body arranged to communicate with said fluid distributing valve, 35 pistons arranged to reciprocate in said cylinders, means for reciprocating said pistons, and preloaded ball bearings mounted between said cylinder body and said distributing valve, the diametral clearances of said preloaded ball bear- 40 45 ings being reduced to substantially zero, the clearance between said cylinder body and said fluid distributing valve being greater than the total diametral clearance of said preloaded ball bearings, said preloaded ball bearings being arranged in paired assemblies at opposite ends of said cylinder body, each of said bearing assemblies including a plurality of rows of preloaded ball bearings.

WALTER ERNST. 50
